W. B. GARDINER

ADJUSTABLE SICK BED

Filed Sept. 6, 1924

Patented Apr. 19, 1927.

1,625,534

UNITED STATES PATENT OFFICE.

WILLIAM B. GARDINER, OF QUINCY, MASSACHUSETTS, ASSIGNOR OF FORTY-EIGHT ONE-HUNDREDTHS TO SEBASTIANO MARCHESE, OF QUINCY, MASSACHUSETTS.

ADJUSTABLE SICK BED.

Application filed September 6, 1924. Serial No. 736,229.

The object of this invention is to provide an adjustable bed particularly intended and adapted for hospitals and other sick rooms, but capable of use in the ordinary way as well, having compact and efficient means for raising either end of the spring or bed bottom, and otherwise equipped for propping up the occupant in a reclining position. The exact nature and utility of the invention 10 can best be explained in connection with the description of a specific embodiment shown in the accompanying illustrations.

In these illustrations:

Figure 1 is a side elevation of my novel 15 bed showing in dotted lines an elevated position of one end of the spring or bed bottom and an inclined position of the back rest;

Fig. 2 is a plan of the bed with parts of 20 the spring or bed bottom broken away;

Fig. 3 is a fragmentary view of the head of the bed with back rest connected thereto.

Figs. 4 and 5 are vertical sectional views 25 of the lower part of one of the bed posts, the planes of section being respectively cross-wise and lengthwise of the bed;

Fig. 6 is in part an elevation and in part a vertical section of the upper end of one of the posts;

Fig. 7 is a perspective view of one of the 30 travellers or elevators for the bed bottom.

Like reference characters designate the same parts wherever they occur in all the figures.

The main or basic structure of the bed 35 may be of any desired character subject to the provisions hereinafter described for operating mechanism. As here illustrated I have made it of a head piece consisting of two posts 1 and 2 and transverse bars or tubes 3, a foot piece consisting of posts 4 and 5 and cross bars 6, and longitudinal side bars 7 which are detachably connected to the head and the foot structures in any suitable manner.

The four posts of the bed are tubular or hollow and each has a slot 8 running along one side. The slotted sides of the head posts are turned toward the foot structure 50 of the bed and the slotted sides of the foot posts are turned toward the head structure. In each post is a longitudinal upright screw 9 mounted at its ends in bearings 10 and 11 which are suitably secured in the posts, conveniently by being screwed therein. A ring-

shaped traveler or nut 12 is fitted to each screw and is adapted to travel lengthwise of the posts when the screw is turned. The several rings or nuts are connected to the corners of the bed bottom and serve to elevate either or both ends of the bed bottom, wherefore I have chosen to call these rings the bed bottom elevators. By the term "bed bottom" I mean that part of the bed on which the occupant lies, and within that meaning are included the usual bed spring of whatever construction desired, and any other mattress support. Each ring is formed with a lug 13 passing through the slot in its post, and to the projecting end of the lug there is connected by a pivot 14, a rod or stem 15.

The bed spring or other mattress support may be of any usual or other suitable construction provided it is made with sockets 75 at the parts adjacent to the posts adapted to receive the rods 15. I have made it with two side bars 16, end bars 17 and a spring fabric 18, and have provided the sockets for the rods 15 by making the side bars 16 80 out of tubes and leaving their ends open. Of course it is understood that these tubes are of the right size internally to fit the bars 15 and permit the latter to slide endwise therein.

On one end of each screw 9, preferably the lower end, is secured a bevel pinion 19 and this meshes with a driving bevel gear 20. The driving gears in the posts 1 and 2 are both mounted on the same shaft 21 which 90 passes across between the posts and has its bearing in them, one end of the shaft projecting from the outer end of post 1 and being square to receive the socket of a crank or wrench 22, shown in Fig. 3. A similar 95 shaft 23 is mounted in the posts 4 and 5 and carries the driving gears in said posts, and is also adapted to be rotated by the crank 22. Thus when either the shaft 21 or the shaft 23 is rotated the travelers in the posts to 100 which that shaft is coupled are raised or lowered simultaneously and the connected end of the spring is correspondingly raised or lowered. The telescopic connection made between the spring and the travelers or elevators, by means of the stems 15 entering the tubular bars 16, permits this motion to take place freely. Thus the whole spring 105 may be raised to any height, or either end may be raised higher than the other to any 110

extent limited only by the height of the posts and driving screws.

A back rest 25 is connected to the head piece of the bed by means of bars 26 and 27 which are pivoted to the upper cross bar of the head piece and have a telescopic connection with the lateral frame members of the back rest, in which they may be adjustably secured by set screws 28. Such back rest 10 may be used to support the occupant's back at an inclination, other than the inclination of the spring as a whole, when either end of the spring is raised above the other, or when it is horizontal and at any height. 15 When needed the back rest may be secured out of the way of the spring by placing its bottom edge in a hook 29 which is mounted on the head structure.

It will be apparent from the foregoing 20 explanation that by means of a very simple compact and inexpensive mechanism, I have provided a means by which the bed may be adjusted to place or support the occupant in any of the positions needed for medical or 25 surgical treatment and in convalescence from illness. At the same time the mechanism is entirely concealed and does not detract from the appearance of the bed. Hence the bed is adapted to be put to ordinary household 30 use subject to use at need for special sick room purposes.

What I claim and desire to secure by Letters Patent is:

1. A bed having corner posts, driving 35 shafts mounted respectively in the two corner posts at each end, each constructed at one end to receive a driving crank, a longi-

tudinal screw contained in each post, a bevel gear on each of said screws, bevel gears on the adjacent shaft meshing with the gears 40 on the screws to rotate the screws, travelers fitted to said screws to progress lengthwise and projecting through slots in the posts, a bed bottom, and pivoted, extensible couplings between said travelers and the bed 45 bottom.

2. An adjustable sick bed comprising a frame having corner posts and connecting bars, screws mounted longitudinally in the 50 several posts, followers threaded on the screws within said posts, each follower having a part projecting through a slot in the side of its post toward the post at the same side and opposite end of the bed, a separate bed bottom having side bars with open 55 sockets in their opposite ends, coupling rods inserted slidably in said sockets, each of said coupling rods projecting from the end of the bar in which it is mounted and having 60 pivotal connection with the part of the follower which projects from the adjacent post, transverse shafts mounted in the two posts at each end of the bed, bevel gears mounted 65 on the screws in the several posts, and complementary bevel gears on said transverse shafts located and arranged in mesh with the bevel gears of the several screws, each transverse shaft being independent of the other and having a protruding end adapted to receive and be rotated by a crank.

In testimony whereof I have affixed my 70 signature.

WILLIAM B. GARDINER.

CERTIFICATE OF CORRECTION.

Patent No. 1,625,534.

'Granted April 19, 1927, to

WILLIAM B. GARDINER.

It is hereby certified that error appears in the printed specification of the above numbered patent requiring correction as follows: Page 2, line 42, claim 1, after the word "lengthwise" insert the word "thereof"; and that the said Letters Patent should be read with this correction therein that the same may conform to the record of the case in the Patent Office.

Signed and sealed this 24th day of May, A. D. 1927.

M. J. Moore,
Acting Commissioner of Patents.

Seal.
